UNITED STATES PATENT OFFICE.

SAMUEL B. HARVEY, OF CHICAGO, ILLINOIS.

FLUE CONSTRUCTION OF GAS-BURNING STOVES OR HEATERS.

SPECIFICATION forming part of Letters Patent No. 717,847, dated January 6, 1903.

Application filed May 5, 1902. Serial No. 105,903. (No model.)

To all whom it may concern:

Be it known that I, SAMUEL B. HARVEY, of Chicago, in the county of Cook and State of Illinois, have invented certain new and useful Improvements in Flue Constructions of Gas-Burning Stoves or Heaters; and I do hereby declare that the following is a full, clear, and exact description thereof, reference being had to the accompanying drawings, and to the letters of reference marked thereon, which form a part of this specification.

This invention relates to improvements in gas-burning apparatus, and refers more specifically to the flue construction of said devices for carrying away the products of combustion and directing the same to the flue-outlet.

I have shown my improvements as applied to a gas-burning water-heater and to a gas-burning stove, the latter construction being associated with the broiling and heating ovens of the stove.

The invention consists in the matters hereinafter set forth, and more particularly pointed out in the appended claims.

In the drawings, Figure 1 is a side elevation of a stove provided with a water-heater to which my invention is applied. Fig. 2 is a horizontal longitudinal section of the water-heater, taken on line 2 2 of Fig. 1. Fig. 3 is a vertical longitudinal section thereof, taken on line 3 3 of Fig. 2. Fig. 4 is a transverse vertical section taken on line 4 4 of Fig. 3. Fig. 5 is a vertical section, taken through a gas-stove including a broiling and heating oven, showing my improved flue construction applied thereto. Fig. 6 is a vertical section taken on line 6 6 of Fig. 5.

First referring to the construction of the water-heater, (shown in Figs. 1 to 4 of the drawings,) A designates as a whole a gas-burning stove, and B a water-heater attached at one side of the stove and at the top thereof. So far as the application of my invention to the water-heater is concerned it bears no relation to the construction of the stove proper, and such parts of the stove need not be specifically described. The application of my invention to a water-heater is shown in Figs. 2, 3, and 4, to which attention is directed in the following specific description thereof. It

may be observed, however, that my improvements may be embodied in a water-heater whether made part of a gas stove or range or whether constructed as a separate device or apparatus. As shown in said Figs. 2, 3, and 4, B' B' designate the side walls of the heater; B² B³, the front and rear walls, respectively; B⁴, the bottom wall, and B⁵ the top plate, which may or may not be made part of the top plate of the stove. Contained within the lower part of the heater chamber or inclosure is a plurality of burner-pipes C C, herein shown as three in number, which extend longitudinally from end to end thereof and are perforated in their upper sides for the emission of the gas. C' designates a transversely - arranged gas-supply pipe or head, from which gas is supplied through mixers comprising contracted discharge-nipples c, communicating with the head, and flaring nozzles or mouthpieces c' on the adjacent ends of the burner-pipes. The supply of gas to said burner-pipes is controlled by means of valves c². When the water-heater constitutes an attachment to a stove, as shown in Fig. 1, the supply pipe or head C' consists of a continuation of the supply-pipe A' of the stove proper. Located above said burner-pipes in position for the flames of combustion to impinge thereon are a plurality of water-heating coils D D, which, as herein shown, have the form of flattened coils, which are connected to form a continuous passage-way for the water and provided at one end with a valved supply-pipe D' and at its other end with a valved discharge-pipe D². B⁶ designates a horizontal plate constituting the top wall of the heating and combustion chamber, in which the burner-pipes and water-pipes are contained and between which plate B⁶ and the top plate B⁵ of the heater is formed the flue-space, through which escape the gaseous products of combustion. Said flue-space is divided by vertical partitions B⁷ B⁸, which extend between the plates B⁵ B⁶ into a central and two side flues b b' b', respectively, and said flues communicate at the rear end of the stove with an exit-chamber B⁹, having a discharge-opening b², surrounded by an annular flange, to which is adapted to be connected a pipe to carry away the products of combustion. The heating and combustion

chamber communicates with the flues b b' through openings b^4 b^4 in the plate B^6 , which constitutes the bottom walls of the flues. The said openings b^4 of the intermediate flue are all located at the front end of the flue, and the rear portion of the bottom wall of said intermediate flue is imperforate, while the openings for the outer flues b' b' extend from one end to the other of the flues. The purpose of so arranging the openings b^4 is to prevent the accumulation of the gases of combustion at the front end of the heater and to insure the escape of the products of combustion from all parts of the heating and combustion chamber uniformly. If the bottom walls of all the flues be perforated throughout their length, the gases of combustion tend to escape more readily through the openings at the rear ends of the flues than at the front ends thereof, whereby the gases of combustion accumulate in the front end of the heating and combustion chamber and tend to escape through the crevices of the heater to the room containing the heater. If the gas burned be natural gas, the escape thereof into the room or apartment is particularly objectionable, owing to the noxious fumes given off by the gas. By arranging inlet-openings to the flues in the manner described—that is to say, by locating all of the openings of one of the flues at the front end of the heater—a free circulation of the gases is established through said flue, which prevents the accumulation of the gases in the front end of the stove in the manner stated. This is due to the fact that the gases of combustion which pass into the front end of the intermediate flue are not checked or impeded by the entrance of gases to said flue between said perforations and the exit-chamber B^8 . As a consequence the rear or imperforate portion of the intermediate flue is maintained highly heated, and the gases which find their way into the front end of said flue are carried by the expansion thereof rearwardly through said flue, whereby a free circulation of the gases is established and maintained, which carries off all of the gases which collect at the front end of the heater. Obviously the same results will be attained whichever one of the flues be perforated at the front end thereof in the manner stated—that is to say, one of the side flues may be perforated at the front end thereof and be imperforate throughout the remaining portion of its length, while the intermediate flue and the other side flue may be perforated throughout their lengths. The construction herein shown is preferable, however, as the front ends of the partitions B^7 may be diverged laterally to enlarge the front end of the intermediate flue, as clearly shown in Fig. 2, and thereby bring said intermediate flue into direct communication with the entire front end of the heater. The construction and relation of the flues may be varied without departing from the spirit of my invention, so long as

the arrangement of the inlet-openings to the flue is retained. The particular construction herein shown, however, is advantageous with respect to economy of construction and is hereinafter specifically claimed. 70

In Figs. 5 and 6 I have shown my improved flue construction applied to a gas-stove for discharging the products of combustion which heat the broiling and baking ovens D D' of said stove. As shown in said figures, the burner-pipes E E are located within the broiling-oven D^a and just below the floor, or lower wall of the baking-oven D^b , and the walls of the baking-oven and the side and back walls D^4 D^5 are formed to provide between the same, on three sides thereof, passages d d' , which communicate with a horizontal space d^2 , located above the baking-oven. f f' designate side and intermediate flues, respectively, which are formed between upper and lower plates F F' and partitions F^2 , said flues being substantially like the flues b b' of the heater before described and communicating at their rear ends with a chamber F^3 , which is adapted for connection with a pipe to carry away the products of combustion from the stove. The lower walls of the side flues in this construction will desirably be perforated throughout their length, as shown at f^2 in Fig. 5, as are the lower walls of the side flues of the heater before described, while only the front end of the lower wall of the intermediate flue is perforated, as shown at f^3 in Fig. 6. The partitions between said flues are also desirably diverged at their front ends to widen the front end of the intermediate flue, as indicated in Fig. 6. The operation of the flues in this construction is the same as that of the heater construction before described. 100 105 110 115 120 125 130

The construction of the top plate of the stove and the burners below the same constitute no part of the present invention and need not be herein described.

It is obvious that changes may be made in the structural details of the flue construction herein described for adapting the same to other forms of heaters or stoves, and I do not wish to be limited to such details except as hereinafter made the subject of specific claims.

I claim as my invention—

1. In a gas-burning heater the combination with the combustion-chamber, of flues arranged side by side above said chamber and communicating at their rear ends with an exit-chamber, the wall of one of said flues being perforated at the front end of said flue only to communicate with the combustion-chamber and the walls of the other flues being perforated throughout the principal part of their length. 110 120 125 130

2. In a gas-burning heater the combination with a combustion-chamber, of at least three flues arranged side by side above said chamber, and communicating at their rear ends with an exit-chamber, the wall of the inter-

mediate flue being perforated at the front end thereof only to communicate with the combustion-chamber, and the walls of the side flues being perforated throughout the principal part of their length.

3. In a gas-burning heater the combination with the combustion-chamber, of flues arranged side by side above said chamber and communicating at their rear ends with an exit-chamber, the wall of one of said flues being perforated at the front end of the flue only to communicate with the combustion-chamber and the walls of the other flues being perforated throughout the principal part of their length, the front end of the first-mentioned flue, being made wider than the other flues.

4. A gas-burning heater comprising a combustion-chamber, burners located in the chamber, the top wall of said combustion-chamber being located a distance below the top plate of the heater, and vertical partitions extending between said top plate of the heater and the top wall of the combustion-chamber which divide said space into a plurality of flues, said top wall of the combustion-chamber constituting the bottoms of the flues and being perforated to communicate with one of said flues at the front end thereof only, and perforated

to communicate with the other flues throughout the principal part of their length.

5. A gas-burning heater comprising a combustion-chamber, burners located in the chamber, the top wall of said combustion-chamber being located a distance below the top plate of the heater, and vertical partitions extending between said top plate of the heater and the top wall of the combustion-chamber which divide said space into a plurality of flues, said top wall of the combustion-chamber constituting the bottom walls of the flues and being perforated to communicate with the intermediate one of the flues at the front end thereof only and perforated to communicate with the other flues throughout the principal part of their length, the front ends of said partitions being diverged to enlarge the front end of the intermediate flue.

In testimony that I claim the foregoing as my invention I affix my signature, in presence of two witnesses, this 12th day of April, A. D. 1902.

SAMUEL B. HARVEY.
